UNITED STATES PATENT OFFICE.

JAMES H. ROBERTSON, OF RUTHERFORD, NEW JERSEY.

DYNAMO-ELECTRIC MACHINE.

SPECIFICATION forming part of Letters Patent No. 399,213, dated March 5, 1889.

Application filed January 29, 1887. Serial No. 225,837. (No model.)

To all whom it may concern:

Be it known that I, JAMES H. ROBERTSON, of Rutherford, Bergen county, New Jersey, have invented a new and useful Improvement 5 in Dynamo-Electric Machines, of which the following is a specification.

My invention relates to dynamo-electric machines; and the objects of my invention are, first, to produce in such a machine an intense 10 magnetic field with a minimum amount of wire, and, second, to concentrate the lines of magnetic force so that all of them will pass through the armature. I accomplish these objects by magnetically connecting the pole- 15 pieces and entirely surrounding them, so that there will be no path for the escape of the magnetic lines of force, and by constructing the armature as hereinafter described and claimed, and so arranging the several parts that their 20 practical construction is simplified and made compact in form, employing no more metal than can be utilized.

In the accompanying drawings, forming part 25 of this specification, Figure 1 represents a vertical cross-section of a machine embodying my invention, the cross-section being taken on line *x x* of Fig. 3. Fig. 2 is a similar cross-section taken on line *y y* of Fig. 3. Fig. 3 represents a horizontal cross-section taken on 30 line *z z* of Fig. 2. Fig. 4 represents the armature prior to the winding of the wire thereon. Fig. 5 shows a transverse cross-section of the armature. Fig. 6 represents one of the disks, with projections, of which the armature is 35 composed. Fig. 7 is one of the plain disks used in the armature. Fig. 8 is a view of the armature with the wires wound thereon secured by binding-wires.

In the drawings, the pole-pieces 1 are formed 40 integral with bases 2, or they may be securely fastened thereto in any suitable manner. I join the bases of the pole-pieces by a section of a hollow iron cylinder, 3, or casing of other suitable shape, the joining being effected by 45 screws or otherwise.

The pole-pieces 1 are wound, as shown in section at 4, and the armature 5, having its shaft mounted in bearings in the side of the cylinder 3, is located between the pole-pieces 50 1, and as near as possible to the same without touching them.

To construct the armature so that it can be easily wound and a good path for the magnetic lines left, without at the same time increasing the facilities for Foucault currents 55 to circulate through it, I place metallic disks 6, having projections 7, together in sets at intervals, with plain disks 8 in smaller sets, the said disks 8 being of the same diameter, excepting the projections, as the disks 6, so as to 60 form a cylinder with grooves 9 about its periphery. The projections 7 also form longitudinal grooves 10, which are filled by the wires 11, wound around from end to end of the armature. The wires 11 are secured in 65 place by binding-wires 12, as shown in Fig. 8, which press the wires 11 into the grooves 9, so that an approximately even surface is formed on the periphery of the armature 5. The wires 12 may be secured in any suitable 70 way—either by tying or soldering them. The several disks, 6 and 8, are magnetically separated and preferably electrically insulated from each other by any suitable insulation. (Indicated by the dark lines in Fig. 4.) 75

The armature as above constructed is mounted on a shaft, 13, the parts thereof extending beyond the armature being non-magnetic. A sleeve, 14, of rubber is interposed between the shaft 13 and the disks, the latter 80 being held in place thereon in any suitable manner—as, for example, by a rib, 15, on the sleeve, located in a groove formed by notches in the disks 6 and 8. If, instead of the armature constructed as above described, plain 85 round disks were used having solid strips of iron fastened at intervals along the periphery of the disks, between which strips wire was wound, it would detract from the current generated, by reason of the local currents set up 90 in the several masses. If non-magnetic material is used, the space occupied by it is wasted so far as adding to the effectiveness of the current is concerned. As this is the part of the machine where every inch of the 95 armature should do useful work, and as the space to do it in is practically limited, it is obvious that by my construction the whole of the armature is utilized.

I claim—

1. In a dynamo-electric machine, an armature formed of a set of disks provided with

- projections of magnetic material, combined with a less number of plain disks arranged at intervals, substantially as described.
2. In a dynamo-electric machine, an armature formed of a set of disks provided with projections of magnetic material alternating with a less number of plain disks, the disks being magnetically separated from each other, substantially as described.
- 10 3. In a dynamo-electric machine, an armature constructed of plain disks placed at intervals among a larger number of disks with projections of magnetic material, the same forming an armature having longitudinal and circumferential grooves, substantially as described.
- 15 4. In dynamo-electric machines, an armature composed of plain disks placed at intervals among a larger number of disks having projections of magnetic material, the same forming an armature having longitudinal and circumferential grooves, and wire wound longitudinally and secured by binding-wires wound in said circumferential grooves, substantially as described. 20

In testimony whereof I have hereunto subscribed my name.

JAMES H. ROBERTSON.
